UNITED STATES PATENT OFFICE.

TRACE S. FORD, OF DES MOINES, IOWA.

DESIGN FOR A COFFEEPOT.

Application filed June 17, 1929. Serial No. 31,737. Term of patent 14 years.

To all whom it may concern:

Be it known that I, TRACE S. FORD, a citizen of the United States, residing at Des Moines, in the county of Polk and State of Iowa, have invented a new, original, and ornamental Design for a Coffeepot, of which the following is a specification, reference being had to the accompanying drawing, forming part thereof.

The figure is a perspective view of a coffee pot showing my new design.

I claim:

The ornamental design for a coffeepot, as shown.

TRACE S. FORD.
